UNITED STATES PATENT OFFICE.

JAMES WRENLEY LEWIS, OF BOLEY, OKLAHOMA, ASSIGNOR OF ONE-HALF TO RANZY BOYKIN, OF BOLEY, OKLAHOMA.

ROAD-MAP SYSTEM AND APPARATUS.

1,272,817.

Specification of Letters Patent. Patented July 16, 1918.

Application filed May 26, 1917. Serial No. 171,122.

To all whom it may concern:

Be it known that I, JAMES W. LEWIS, a citizen of the United States, residing at Boley, in the county of Okfuskee and State 5 of Oklahoma, have invented certain new and useful Improvements in Road-Map Systems and Apparatus, of which the following is a specification.

The invention has for an object to provide 10 means whereby tourists on long trips through strange territory may readily find their way without requiring to be provided with maps of the entire route, and to enable them to select various routes in the 15 same general direction without danger of being lost. The invention is also useful in enabling the provision of a means for locating a given route over a great distance, without requiring the mapping of a large portion 20 of territory not involved in following the route, although permitting some latitudes in alternative roads in given vicinities.

A further important aim of the invention is to present desirable means for presenting 25 the information and in a systematic manner which will assure proper guidance of persons going in either direction upon a given route.

A further purpose is to give a desirable 30 construction in means for holding a map in convenient position to be read by autoists or others in vehicles, without requiring them to dismount. A further aim is to give such a device which will readily enable the 35 emplacement of a map, and which will protect it effectively from the elements.

Additional objects, advantages, and features of invention will appear from the construction, arrangement and combination of 40 parts hereinafter described and particularly shown in the drawings, wherein—

Figure 1 is a portion of a map indicating a part of a general route from the eastern United States to the far West.

Fig. 2 is a detail of a map stand,

Fig. 3 is a detail top view of the base portion of the stand,

Fig. 4 is a detail of one of the maps,

Fig. 5 is a detail of the mounting of the 50 protecting cover for the map,

Fig. 6 is a detail of the supporting plate for the map,

Fig. 7 is a top view of the folding box for the map.

55 There is illustrated in Fig. 2 a stand base

10, including the hollow post portion 11 suitably set in the ground, and formed with transverse openings therethrough, through which a suitable heavy cross bar 12 is inserted to form an anchor. The upper end 60 of the post is provided with branched arms 13, five in number, one being extended vertically, while the others are directed outwardly in diagonal fashion, the ends of all the arms being located in a common plane 65 and smoothly finished to receive a planiform box element 14 which will be subsequently described in greater detail. The extremities of the diagonal arms 13 are located at the corners of an oblong rectangle, the major 70 dimension of which extends in a direction at right angles to the axis of a hinged cover 15 upon the box 14, so that in the use of the latter the liability of the box becoming loosened upon the base will be minimized. 75

The box is circular in plan, and comprises a bottom plate having a circumscribing vertical flange 17 therearound upon which there is secured a ring 18, projecting inwardly of the flange 17 a short distance, to serve as a 80 retainer for the contents of the box. Suitable ears 19 are formed at one side, between which there is pivoted the hinge knuckle 20 of the lid 15 before mentioned, which is circular in form and of a size to lie snugly 85 over the ring 18 with its edges alined with the edges of the ring and flange 17. The flange 17 is formed at the forward side with a slight rounded projection 21, and the lid 15 is formed with a spring 22 suitably 90 formed to snap over the projection and hold the lid yieldably in closed position. Removably set within the flange 17 upon the plate 16, there is a circular plate 23, upon which there is cemented a map 24, which will subsequently be explained in detail, and a disk 25 of glass is superposed upon the map, this glass also fitting snugly within the flange 17, the map with its base, and the covering glass being of a thickness to fall 100 just below the ring 20, so that the latter will hold them snugly in place and prevent access of dust around the edges. This result may be assured by laying one or more pieces of paper beneath the plate 23, if necessary. It 105 may be found desirable to provide some means for limiting the upward movement of the lid 15, whereby it will tend to close, so that the latter may not be thrown backwardly and forgotten, creating the liability 110

that rain may cause accumulation of water upon the glass 25. It may also be found desirable to provide some well known gasket material between the ring 18 and the glass plate 25, this not being illustrated as it is thought sufficiently obvious.

In use, a plurality of the posts and the boxes assembled as described are located beside certain highways, as indicated at *a*, *b*, *c*, 10 in Fig. 1. The map at each point will include an area within a circle or other boundary that will fall immediately adjacent or include the next adjacent points at which one of the devices is located, as shown by the 15 circles A, B, C, in Fig. 1. The stations are preferably located at equal distances apart, on a given route and the map so drawn that its boundaries will fall near or include the next adjacent station in each direction upon 20 the route involved. In this way the map displayed at a given station will duplicate one half of the route mapped on the next adjacent station, showing the route between the respective stations. This is necessary 25 in order that a person going in either direction upon a particular route will be able to obtain information at each station which will enable him to find his way to the next one. If desired, the stations may be located 30 at closer distances than the centers upon which the maps are based, as for instance indicated at *b'*, *b''*, in Fig. 1, at which points, as well as at the point *b* in the figure mentioned, a map such as illustrated in Fig. 35 4 will be displayed at the station, the area upon this map corresponding to that within the circle B shown in Fig. 1.

The method particularly illustrated herein is especially adapted to use in marking

off a cross country highway or transcontinental road, and has been found especially advantageous for such uses. It will be seen that a method is offered extremely simple and well adapted to popularize American tours making it possible for the public to find 40 its way without being required to carry maps, in unfamiliar territories. The construction of the map casings is extremely simple, and the method and apparatus are adapted to be put into use at a compara- 45 50 tively low cost.

While the maps indicated are based upon centers having a certain spacing with regard to the actual distances involved, it will be readily understood that these may be spaced 55 farther apart than illustrated, and if desired certain of the maps, especially those in sparsely populated sections may include a much larger area of territory than others upon the same route, these being matters of 60 discretion in the utilization of the invention.

The map holding devices may be located in small booths built beside the roadway, if desired, as will be readily understood which may be locked if desired, and keys provided 65 for persons desiring to use the maps.

What is claimed:

The combination of a plurality of maps of certain divisions of terrain, the divisions mapped overlapping, whereby the map of 70 one division will show one half of each of the next adjacent divisions.

In testimony whereof I have affixed my signature in presence of two witnesses.

JAMES WRENLEY LEWIS.
